LUGGAGE CASE

Tim M. Uyeda, Los Angeles, Robert S. Inlow, Pasadena,
James M. Powell, Anaheim, and Robert K. Fujioka,
Los Angeles, Calif., assignors to Shwayder Bros., Inc.,
Denver, Colo., a corporation of Colorado

Application September 23, 1957, Serial No. 47,826

Term of patent 14 years

(Cl. D87—5)

FIG. 1.

FIG. 2.

Fig. 1 is a front perspective view of a luggage case embodying our new design; and

Fig. 2 is an end perspective view of the luggage case of Fig. 1, the rear and bottom of the luggage case being conventional.

We claim:

The ornamental design for a luggage case, as shown and described.
